United States Patent Office.

GEORGE B. KIRKHAM, OF NEW YORK, N. Y.

Letters Patent No. 74,916, dated February 25, 1868.

IMPROVEMENT IN STRAP-HOLDER.

The Schedule referred to in these Letters Patent and making part of the same.

TO ALL WHOM IT MAY CONCERN:

Be it known that I, GEORGE BYRON KIRKHAM, of 167 East Thirty-Third street, city, county, and State of New York, have invented a new and useful Improvement in a Strap-Holder; and I do hereby declare the following to be a full, clear, and exact description of the same, sufficient to enable one skilled in the art to which the invention appertains to make use of it, reference being had to the accompanying drawings, which form a part of this specification, and in which—

Figure 1 represents the straps and the fastener complete.

Figure 2 shows the body of the holder and the fixed strap.

Figure 3 represents the movable slide, with its fixtures.

Figure 4 shows the catch at the end of the holder; and

Figure 5 the spring that secures this catch.

This improvement is designed to fasten movable straps and everything of the kind which it is desirable to hold securely, acting at once in the capacity of a buckle and a-loop, together or separately, as may be wanted.

The main body of the holder is fastened to the fixed strap by tacks passing through it and the strap, and riveted on the side opposite to the strap, as represented at fig. 2. At one end of this holder are grooves or ridges, *a a*, in which moves the slide, with corresponding grooves or ridges. This slide is corrugated, or has teeth on the under side, which grip into the movable strap, and as the slide is pushed down, it presses on the strap, and holds it firmly. The slide has a little bent wire, *b*, sliding in a slot, to hold it in place; also, as a precaution against its being lost, a little chain, *c*, attaching it to the main holder. The catch, fig. 4, at the other end of the holder, has a groove to hold the strap, and two depressions, *d d*, into which a spring, fig. 5, slips and holds it open or shut.

Having described my invention, what I claim therein as new, and desire to secure by Letters Patent, is—

The body of the holder as adapted with the slide, the bent wire *b* and chain *c* at one end, and as adapted with the catch and spring at the other end, all as herein described.
